UNITED STATES PATENT OFFICE.

ERNEST C. ALLEN AND FELIX J. MUELLER, OF WEST ALLIS, WISCONSIN.

ROTARY ENGINE.

1,135,750.

Specification of Letters Patent. Patented Apr. 13, 1915.

Application filed February 24, 1914. Serial No. 820,690.

To all whom it may concern:

Be it known that we, ERNEST C. ALLEN and FELIX J. MUELLER, citizens of the United States, residing at West Allis, in the county of Milwaukee and State of Wisconsin, have invented certain new and useful Improvements in Rotary Engines, of which the following is a specification.

Our invention relates to certain new and useful improvements in rotary engines, of which the following are some of the main objects; first, to provide an engine of this character which is reversible in its direction of rotation and in which balanced conditions exist in a high degree at all times; second, an engine of the above type which is simple and inexpensive in construction, and capable of developing great power, and which is readily assembled and taken apart; third, an engine of the above character which is of a compound type, and suitable for both condensing and non-condensing operations; fourth, a rotary engine in which a combination of specially constructed valves of the rotary type are employed to affect the admission, the cut-off of the pressure fluid to the high pressure chambers and thence to the low pressure chambers, and the regulation of the exhaust port opening.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

For full understanding of the invention, reference is to be had to the following description and accompanying drawings in which:

Figure 1 is a longitudinal sectional view through the complete engine, said section being taken upon line M—M as shown in Fig. 2 looking in the direction of the arrows. Fig. 2 is a section taken on line A—A of Fig. 1 illustrating the positions of the high and low pressure abutting valves with respect to the rotating pistons at the beginning of a stroke. Fig. 3 is a front elevation showing the inlet pipe connections. Fig. 4 is a rear elevation thereof disclosing exhaust pipe connections and reversing gear.

Fig. 5 is a detail section on line B—B Fig. 1 showing the means of controlling the abutting valves. Fig. 6 is a detail section on line C—C Fig. 2 showing the construction of the high pressure abutting valves. Fig. 7 is an end view of a low pressure abutting valve looking on the inlet side. Fig. 8 is a detail section on line D—D Fig. 2 showing the construction of the low pressure abutting valves. Fig. 9 is a perspective view of a rotary admission and cut-off valve. Fig. 10 is a detail sectional view of the form of packing interposed between the moving and stationary parts. Fig. 11 is a detail view showing one of the rotary pistons with packing strips in place.

In these drawings like characters of reference indicate corresponding parts in each figure.

The preferred form of construction as illustrated in the drawings comprises a stationary cylindrical casing or stator consisting of end members 1 and 2 which are formed at the under sides with bases whereby the engine may be mounted upon and secured to a suitable support. Arranged between these members is an intermediate partition 3, said members and partition being rigidly secured together at intervals by means of bolts 4.

A shaft 5 is mounted in bearings 6 and 6', which are supported by the pedestals 7 and 7'. Said pedestals being rigidly fastened to the above mentioned end members by means of bolts 4'. At the points where the shaft 5 extends through the end members special sealing glands comprising 8, 9, 10, 8', 9' and 10' are employed to confine the leakage pressure fluid within the walls of the stator. In this sealing gland 9 and 9' are rings fixedly disposed with respect to the end members 1 and 2.

8 and 8' are rings fixedly disposed with respect to the shaft 5. Grooves are formed in the adjacent faces of 8, 9, 8' and 9', forming annular recesses for receiving the sealing rings 10 and 10'. The screws 11 also disposed in the end members 1 and 2 provide for longitudinal adjustment.

Mounted upon and rigidly secured to shaft 5 by means of keys is a plurality of rotors 12 and 13. Said rotors are of a diameter less than that of the interior of the stator, so that annular spaces are formed around the peripheries of the said rotors. Said spaces thus formed around the peripheries

of the said rotors are divided by the intermediate partition 3 thus forming a series of initial and expansion chambers which are independent of each other. By means of 5 packing rings 16 disposed in annular grooves between the adjoining faces of the rotors and the stator, the amount of leakage pressure fluid is reduced to a minimum.

Disposed about the peripheries of the 10 rotors 12 and 13 and securely fixed thereto by means of the bolts 17 is a plurality of pistons 18, 18' arranged in pairs, that is, each piston having a like one placed diametrically opposite. The pistons 18 and 18' 15 form a plurality of separate initial pressure fluid chambers 14 and 14' in the annular space between the rotor 12 and the stator, and in a like manner the pistons 18 and 18' carried by the rotor 13 and which are of the 20 same number and in longitudinal alignment with these, form a plurality of expansion chambers in the annular space between the rotor 13 and the stator. These pistons 18, 18' are also supplied with packing strips as 25 detailed in Fig. 11, forming a snug fit with the walls of the pressure fluid chambers. Main initial pressure fluid controlling valves 20 and 20', cylindrical in shape, which are to be restricted to a certain oscillatory motion by external means, not disclosed in the 30 drawings, but communicating with the same through the stems 21 and 21' which form parts thereof. Said stems extend through glands 22 and 22' disposed in the walls of 35 special inlet pipe connections, preventing any leakage of pressure fluid to the atmosphere. The function of these rotary controlling valves is to regulate the time of port opening and cut-off. Said valves are disposed in rotary abutting valves 25 and 25', 40 these abutting valves, arranged in pairs about the peripheries of the rotor 12, are located in cylindrical recesses formed in the end member 1 and placed diametrically opposite each other, having the ports of said 45 rotary controlling valves 23 and 23' communicating respectively with the passages 24 and 24' which are formed in said rotary abutting valves. By means of this combination of ports and passages the pressure fluid is admitted at either side of the vertical center line of these valves depending upon the 50 direction of rotation desired. The arrangement of these combinations of valves as described, permit the pressure fluid to be simultaneously admitted and cut-off at points diametrically opposite, thus resulting in a high degree balanced conditions about the rotor at all times, it being understood 55 that the area of the port openings in each set of diametrically placed valves are of the same size.

After the pressure fluid is admitted to the initial chambers variable cut-offs occur in 60 order to maintain regulation of speed under

variable loads. These cut-offs are brought about by the external means heretofore mentioned, through communication with the valve stems 21 and 21'. At admission the pistons 18 and 18' receive an impact from the pressure fluid and advance forward under the initial pressure of the pressure fluid to the point of cut-off, the remainder of the stroke being completed by the expansive force of the pressure fluid. From these 70 chambers admission to the low pressure chambers is brought about by means of passages 27, 28 and 28' formed in the low pressure abutting valves 29 and 29', said admission necessarily occurring immediately after 75 pistons 18 and 18' pass the points 30 and 30'. Said low pressure abutting valves which are located in cylindrical recesses formed in end member 2 and intermediate member 3, are placed about the periphery of rotor 13 diametrically opposite each other and in longitudinal alignment with their corresponding initial pressure inlet valves and rotary abutting valves. The manner in which the rotary abutting valves 25, 25', 29 and 29' are engaged and held together at their adjacent 80 ends provides for a free oscillatory motion of said valves. It is evident from the drawings that the oscillatory motion above mentioned is brought about by the rotating pistons 18, 18', which serve as cams. By reason of the function which is thus served by said pistons the opposite sides are inclined in order to permit of a gradual raising and lowering of said valves. The lowering being 85 brought about under the influence of helical compression springs 31 and 31' interposed in special exhaust connection 35. The rotary abutting valves are provided on their under sides with shock absorbing springs 33 which tend to reduce the jar upon them caused by 90 the rotating pistons. The lowering being 95 brought about under the influence of helical compression springs 31 and 31' interposed in special exhaust connection 35. The rotary abutting valves are provided on their under sides with shock absorbing springs 33 which tend to reduce the jar upon them caused by 100 the rotating pistons.

The pressure fluid after being thoroughly expanded in the low pressure expansion chambers 15 and 15', passes through suitable 105 openings 34 and 34' provided in end member 2, then into the special exhaust connection 35 and 35'. As can be seen from the different views provision for ample area of exhaust openings are made by means of the 110 specially constructed low pressure abutting valves.

Means is provided for changing the direction of rotation of the engine. The reversing of the engine is brought about by means 115 of a reversing lever 36. This lever is securely fastened to the valve stem 37 and by engaging the end of this stem with slots 38 and 38', suitably formed in the end of the low pressure abutting valve, then turning 120 said valve by means of lever 36 bringing the opposite faces of the abutting valves into play as abutments and thereby transferring the pressure fluid inlet to the opposite side of the vertical center line of the valve com- 125 130

binations. As before stated the motion of the different abutting valves is influenced by the springs 31 and 31' which are received and fastened at one end in specially formed recesses provided for in the special exhaust connection 35. The springs 31 and 31' are employed in turn depending upon the direction of rotation desired. The influence of the springs being transmitted to the rotary abutting valves through the wing 39 which forms a part of the valve stem 37. It is evident in reversing that the angularity of the rotary abutting valves with respect to their vertical center line must be changed. Said change necessitates the force which influences the motion of said valves to be transferred to the opposite side of the vertical center line of the valves, this change being brought about by withdrawing the valve stem 37 from its slots provided in the low pressure rotary abutting valve, then turning lever 36 together with stem 37 through the required angle to permit engagement with the other slot provided. In this operation the wing 39 is brought up against the free end of the opposite acting compression spring thus bringing its influence into operation.

By means of connecting rod 42 linked to levers 40 and 41 any change in the angularity of either combination of valves while reversing will be transmitted to the diametrically oppositely disposed combination of valves. At the same time this mechanism serves to transmit the influence of the springs acting upon the first combination of valves, to those of the second combination oppositely disposed. At the points where the stems 37 and 37' project from the special exhaust connections 35 and 35', suitable packing glands 43 and 43' are provided. These glands prevent leakage of the pressure fluid from the exhaust connections and in condensing operation prevent air from leaking in.

Copies of this patent may be obtained for five cents each, by addressing the "Commissioner of Patents, Washington, D. C."

Having thus described the invention, what we claim as new and desire to secure by Letters Patent is:—

In a compound rotary engine; a casing divided into high and low pressure rotor receiving compartments and having substantially diametrically oppositely arranged abutment receiving chambers disposed adjacent the compartments; high and low pressure rotors arranged within the high and low pressure compartments respectively; swinging hollow abutments arranged within the abutment receiving chambers, each abutment comprising a high pressure abutment-section discharging into the high pressure compartment and a low pressure abutment-section receiving the exhaust from the high pressure compartment and discharging into the low pressure compartment, each abutment-section having its opposite ends open and adapted to be brought to covered and uncovered positions whereby the direction of rotation of the rotors may be reversed; mechanical connections between the abutments whereby they may be simultaneously turned in reversing the rotors; spring operated means to automatically return the discharging end of each abutment-section to the operative position when moved therefrom by the corresponding rotor during the operation of the rotor; a tubular valve arranged within each high pressure abutment-section to be turned therein for regulating the passage of fluid pressure through the same; and means for simultaneously supplying fluid pressure to the high pressure abutment-sections.

In testimony whereof we affix our signatures in the presence of two witnesses.
